CLAIM

The ornamental design for a display screen or portion thereof with graphical user interface, as shown and described.

DESCRIPTION

The file of this patent contains at least one drawing/photograph executed in color. Copies of this patent with color drawings will be provided by the Office upon request and payment of the necessary fee.

FIG. 1 is a front view of a display screen or portion thereof with a graphical user interface showing a first embodiment of our new design;

FIG. 2 is a front view of a display screen or portion thereof with a graphical user interface showing a first image in a sequence showing a second embodiment of our new design;

FIG. 3 is a second image thereof;

FIG. 4 is a front view of a display screen or portion thereof with a graphical user interface showing a third embodiment of our new design;

FIG. 5 is a front view of a display screen or portion thereof with a graphical user interface showing a fourth embodiment of our new design;

FIG. 6 is a front view of an exemplary electronic device on which the graphical user interface designs of FIGS. 1-5 can be displayed; and,

FIG. 7 is a front view of an exemplary electronic device on which the graphical user interface designs of FIGS. 1-5 can be displayed.

The graphical user interface shown in FIGS. 1-5 may be displayed in a similar manner as shown in FIGS. 6 and 7. The broken lines in FIGS. 1-5 depict portions of the graphical user interface that form no part of the claimed design. The broken lines depicting a display screen, portions of the graphical user interface, and electronic devices in FIGS. 6 and 7 form no part of the claimed design.

Portions of the graphical user interface in FIGS. 2, 3, and 5 are illustrated with color.
